UNITED STATES PATENT OFFICE

ALBERT SLETTEN, OF FARGO, NORTH DAKOTA.

PHOTOGRAPHIC-PRINTING MACHINE.

1,209,631.

Specification of Letters Patent. Patented Dec. 19, 1916.

Application filed November 27, 1915. Serial No. 63,778.

To all whom it may concern:

Be it known that I, ALBERT SLETTEN, a citizen of the United States, residing at Fargo, in the county of Cass and State of North Dakota, have invented new and useful Improvements in Photographic-Printing Machines, of which the following is a specification.

My invention relates to certain new and useful improvements in photographic printing machines, and one object of the invention is to provide a machine of this character which is adapted for printing from either separate or roll films or plates, at will.

A further object of the invention is to provide a photographic printing machine which facilitates the operation of disposing in printing position a mask or cut-out of proper size, which provides for the use of paper from a roll and the cutting of the paper as required, either into individual prints or a series of prints in a strip, which also provides for the automatic feeding of the paper in position, and which facilitates and reduces the amount of time and labor required in placing the film or plate in proper position in connection with the required mask or cut-out, the feeding and printing of the paper and the other necessary operations.

A still further object of the invention is to provide a photographic printing machine which is simple of construction, reliable and efficient in operation, and which is adapted to feed the proper amount of paper to printing position, and which can be readily and conveniently arranged to print from single films or glass negatives or a strip of films from a roll, as desired.

With these and other objects in view, the invention consists of the features of construction, combination and arrangement of parts herein fully described and claimed; reference being had to the accompanying drawings in which:

Figure 1 is a front elevation of a photographic printing machine embodying my invention, showing the parts in normal position. Fig. 2 is a top plan view showing the parts in printing position, as in printing from a film. Fig. 3 is a vertical transverse section on the line 3—3 of Fig. 2. Fig. 4 is a rear elevation, showing in full and dotted lines the film and paper clamp and the operating parts of the paper feed mechanism

disposed in the position shown in Figs. 1 and 2. Fig. 5 is a vertical transverse section showing the paper knife operated with the clamp for a cutting action. Fig. 6 is a horizontal transverse section on the line 6—6 of Fig. 1. Fig. 7 is a vertical front to rear section through the apparatus taken on the line of the axis of the light chamber. Fig. 8 is a sectional view on the line 8—8 of Fig. 2, showing the paper feed device associated with the paper feed roll and showing in full and dotted lines the operation thereof. Fig. 9 is a detail view of the combined paper guide and stationary cutting knife. Fig. 10 is a view showing certain features of construction of the clamp and knife actuating mechanism. Fig. 11 is a front elevation showing the application of a glass negative holder. Fig. 12 is a vertical longitudinal section through the holder. Fig. 13 is a similar view thereof showing the back of the holder open. Fig. 14 is a section on the line 14—14 of Fig. 12. Fig. 15 is a plan view of the mask ring or cylinder as it would appear in flattened condition.

Referring to the drawings, 1 designates a suitable supporting frame upon which is mounted a light box or chamber 2, which is herein shown as of substantially cylindrical form, the upper portion of said box being cut away to provide a printing space or opening 3, communicating with a doorway or space 4 in the front of the box which is adapted to be closed by a lid or cover 5, and serves as a sight opening, through which the operator may inspect the adjacent inclosed working parts whenever desired. This doorway 4 also provides for the ready and convenient insertion and removal of one or more ground glass or other suitable light diffusing plates 6, through which the light rays from one or more lamps inclosed within in the light box or chamber may be properly transmitted to the opening 3 for the printing operation. In practice, a ruby lamp in connection with one or more ordinary lamps of the incandescent type may be employed, and connected with a source of current supply and a switch mechanism whereby the red and white lights may be simultaneously and alternately thrown into and out of action at the will of the operator, for purposes well known to those versed in the art.

Surrounding the circular light box or

chamber is a drum or rim 8 of glass or other suitable transparent material, which is provided with opaque portions 8 dividing or setting off the surface of said ring to 5 provide a desired arrangement and number of masks or "cut-outs" 9, in the form of light transmitting areas, any one of which may be brought into position in registry with the light opening 3 according to the 10 size or character of the negative which is to be printed from, whereby any selected mask may be conveniently adjusted for use and the time and labor involved in cutting out and applying different masks for different 15 negatives saved. A turn-button or other suitable fastening member 10 is provided for holding the mask ring in position, but upon the retraction of this turn-button the ring may be removed, so that rings of different 20 character may be employed interchangeably.

A negative and paper clamping device 11 is provided for clamping the negative and paper against the portion of the surface of 25 the mask ring registering with the opening 3, and this clamp comprises a block of rectangular or oblong rectangular form and having an inner concaved surface to fit the circumference of the cylinder, said surface 30 being provided with a facing 12 of felt or other suitable material to snugly engage the paper and film to bring the same into close abutting relation without injury thereto. This clamp is hinged, as at 13 to swing from 35 a substantially horizontal or printing position back to a substantially vertical retracted or inoperative position, and to the outer or rear surface of this clamp is slidably and pivotally connected one end of an arm 14 40 projecting at right angles from a rock shaft 15, having another arm 16 provided with an actuating grip or handle 17, by means of which the clamp may be moved into and out of printing position. The handle 17 is pro- 45 vided with a guard or guide member 18 for a purpose hereinafter described, and carried by the clamp is an auxiliary clamping or centering device comprising a head 19 carried by a stem 20, said head and stem 50 being slidably movable through a guide member 21 communicating with a receiving opening 22 in the body of the clamp, the head 19 being normally held projected by a spring 23. When the clamp is moved into 55 position to engage the paper and film, the auxiliary clamping head 19 first engages the paper and film and holds the same centrally while the concaved face of the clamp moves into clamping position, thus preventing the 60 paper and film from shifting out of proper relationship and at the same time insuring the spreading out of the paper without wrinkling as the clamp comes into contact therewith. A pin 24 passes through the stem 65 to detachably hold the auxiliary clamping

device in place and also serves as a stop to limit the inward or forward movement thereof.

Supported upon the frame is a spool or reel 25 containing a roll of sensitive paper 26, the free end of which is adapted to pass between the surface of a rotary feed roll 27 and a co-operating idler or friction roll 28, whereby the paper is adapted to be securely gripped and fed forward. The paper passes from the rolls 26 and 27 across the face of a guide plate or block 29, which is provided with guide members 30 and 31. The guide member 30 is fixed, while the guide member 31 is provided with a dove-tailed projection 32 to engage a dove-tailed groove or guideway 33 in the plate, whereby said guide member 21 may be adjusted toward and from the guide member 30 to suit any desired width of paper, a handle 34 being provided for adjusting the said guide member 31 in a convenient manner. The edge of the guide member adjacent to the printing opening 3 is provided with a fixed or stationary cutting blade 35, and said 90 guide plate is hinged or pivoted at its rear end to the support, as shown at 36, so as to be swung from a normally horizontal working position to an inoperative position, and a spring or other elastic connection 37, which 95 is detachably fastened to the light box, is provided for holding said guide plate down normally in guiding position while permitting of its detachment and upward and backward movement to an inoperative position, as hereinafter fully described. The idler 28 is carried by a swinging arm 38 which is normally disposed to hold said idler in peripheral contact with the feed roll by means of a spring or other elastic ele- 100 ment 39, but the free end of this arm is movable to throw the idler out of engagement with the feed roll and into engagement with a latch 40, whereby the idler may be held in such position, thus allowing the 105 paper to be threaded and unthreaded in a ready and convenient manner at different times in the use of the apparatus.

Mechanism actuated by the movement of the clamp is provided for operating the feed roll 27 and feeding the paper to printing position. This mechanism comprises a connecting rod 41 having a bifurcated and slotted end portion 42 receiving a crank arm 43 carried by the rock shaft 15, said arm being perforated to receive a fastening pin 44 slidably and pivotally connecting the same with the bifurcated and slotted end of the connecting rod, whereby in the operation of the rock shaft the rod will be reciprocated. The rod 115 is connected with one arm of a pivoted lever 45, arranged upon the back of the supporting frame 1, and the other arm of which is coupled by a connecting rod or link 46 with a swinging feed arm or lever 47 loosely jour- 120 125 130

naled upon the frame and provided with ratchet teeth 48 to engage a dog or pawl projection 49 upon the feed roll, whereby in the working movement of said swinging arm the roll will be turned a prescribed distance while on the reverse or retractive movement of the arm the teeth of the wheel will slide over the point of the dog without turning the feed roll. The free end of the arm 47 is arranged to sweep in an arc across a portion 50 of the surface of the frame, in which is formed a series of openings 51 to receive a stop pin 52 whereby the swinging motion of the arm may be controlled, and said arm permitted to move to varying distances within a maximum mark to feed a greater or less amount of paper to printing position. The surface 50 may be provided with a suitable scale arranged in proper relationship to the openings to indicate which particular opening the stop pin should be inserted in to feed a quantity of paper sufficient for any size negative into printing position. The variable range of feed motion of the swinging feed arm is permitted by reason of the slot and pin connection between the same and the reciprocating rod 41, as will be readily understood.

For the purpose of arresting the motion of the feed roll the instant the motion of the feed arm is arrested, an automatic stop device is provided, and comprises a headed brake member 53 carried on the swinging arm and movable into and out of engagement with the feed roll, said brake member being pivotally connected with a cam or eccentric 54, which is coupled by a link or connecting rod to a V-shaped or forked trip member 55 pivoted to the swinging arm and adapted to be held in either position beyond center by a spring 56 to lock the brake in both projected and retracted positions. The trip fork 55 is adapted to engage the stop pin 52 in such manner that one of the arms 45 of the work will engage the pin to throw the brake into action when the feed arm reaches the limit of its movement, and on the return movement of the feed arm the other arm of the trip fork will engage the pin and retract 50 the brake to release the drum for the succeeding feeding motion. It will thus be apparent that the feed mechanism may be set to feed a quantity of paper sufficient for a negative of any given size within predetermined limits, and that as soon as the paper is fed into position the motion of the feed roll will be stopped to prevent the supply of an excess amount of paper.

In practice, the paper may be supplied for each printing action and clamped in position with the film by simply moving the hand lever 17 downward, in which operation the paper feed mechanism will be actuated, while upon swinging the handle upwardly and rearwardly the clamp will be retracted to re-

lease the negative and printed paper. For use in connection with the paper feeding and clamping means and the stationary cutting knife 35 upon the guide plate 29, I provide a movable cutting knife 56' which is arranged for movement on a line between the clamping device and the guide plate and is carried by a rock shaft 57 having a handle 58 provided with an arm 59 arranged at right angles thereto, and which is adapted 75 when the handle 17 is retracted to extend across the arm 16, the handle 58 in this position lying in the space between the arm 16 and the guard 18. It will thus be understood that after the paper is fed up and 80 printed, the movable cutting knife may be swung downwardly and forwardly to cooperate with the cutting knife 38 to sever the printed portion of paper from the roll or strip, and that in this position the actuating handle and arm of the movable knife will lie in the path of the clamped handle, so that when said clamped handle is swung backward to retract the clamp the movable knife will also be retracted. This construction 85 also adapts the movable knife to be moved downward with the clamp to sever the paper from the roll at the time it is clamped, since both handles may be simultaneously grasped and moved downward and 90 forward, while at the same time permitting the clamp to be moved downwardly and forwardly alone, so that a continuous series of prints may be made without actuating the movable cutting knife. It will thus be understood that where but a single print is to be made of any negative, the paper may be cut at the time the clamp is thrown into 95 action, while if two or more prints are to be made from the same negative the paper may 100 be intermittently fed up for each print until the required number are made without operating the cutting knife, the knife being operated at the end of the series of printing actions so that all of the prints may be made 105 upon an intact strip of paper. This operation may also be pursued when it is desired to print a series of different pictures upon a continuous strip of paper, as will be readily understood.

As described, the individual films may be successively clamped in position by the clamping device, but if desired a roll of film containing a series of pictures may be placed in position for successively printing the pictures thereon. When this is done, the film roll 60 is placed around the revoluble mask cylinder and secured in position by spring clips 61 engaging the ends thereof, said clips having an elastic connection 62, whereby the 115 film may be held in place in such a way that films of different lengths may be applied and so that each film roll may be slipped around in position for successively printing through the different negative portions 120 125 130

thereof, as will be readily understood. In order that the size of the opening 3 may be varied to suit different sizes of negatives, segmental shutters 63 are provided at the 5 opposite sides of said opening and are normally held retracted by springs 64, said shutters being coupled by winding connections 65 with a winding shaft 66 provided with a crank handle 67, whereby said shutters may be adjusted toward or from each 10 other to vary the size of the opening 3 as required, a suitable latch mechanism 68 being provided to secure the shutters in adjusted position. If desired, a clamp 69 may 15 be provided at the rear portion of the light opening 3 to engage and hold separate films and pieces of paper temporarily in position prior and subsequent to the clamping action of the clamping device 11, and this clamp- 20 ing member may be pivotally supported by mounting it upon a rock shaft 70 having at one end a handle 71 pressed by a spring 72 to normally maintain said clamp in position.

The guide plate 29 is adapted, upon dis- 25 connecting its spring or elastic connection 37 from the light box, to be turned upwardly and backwardly to a vertical position, so that when the guide plate is so ad- 30 justed and the clamping device and knife 35 are also turned back a holder 73 may be applied to the mask cylinder in line with the light opening 3 for holding glass negatives in position to be printed. This holder comprises an open rectangular frame having a concaved face to fit the mask cylinder and provided upon the interior thereof with ledges or shoulders 74 against which the glass plate or negative 75 may rest. When applied in position for use, the holder may 40 be secured to the light box by hooked fastening members 76 engaging keeper pins or studs 77 upon the front of the light box. The outer side of the holder frame is adapt- 45 ed to be closed by a back or cover 78 composed of a pair of sections hinged to each other, as indicated at 79, and hinged or pivoted at one end to the box frame, as in- 50 dicated at 80, the opposite or free end of the cover being connected by a link 81 with a hand lever 82 pivoted to the frame, and 55 whereby the cover may be closed to clamp the negative and paper in position or opened for the removal of the same. By means of the link motion may be transmitted to the cover from the lever for positively opening and closing said cover, and coiled springs 83 are provided upon the lever and cover which are tensioned when the lever is moved to closed position to apply the yielding pres- 60 sure to clamp the cover in applied position, as will be readily understood. At its free end the lever is provided with a latch 84 to engage a keeper 85 on the frame, for securing the lever in closed position. The front 65 of the frame is cut away at its upper edge

to form a space for the reception of a paper guiding and cutting blade 86 which is pivotally supported by a rock shaft 87 having a crank handle 88, so that the blade may be tilted to permit the paper to be inserted be- 70 tween the same and the adjacent surface of the frame, it being evident that when the paper is applied to lie in contact with the negative it will be held from displacement by the blade and upon being so applied the exact amount of paper may be cut off from an endless strip. The use of the holder per- 75 mits of prints being made from negatives with the same degree of efficiency and ce- 80 lerity as in making prints from films.

From the foregoing description, taken in connection with the drawings, the construction and mode of operation of my improved photographic printing machine will be readily understood, and it will be seen that the invention provides a machine of this character which is simple of construction, reliable and efficient in action, and adapted to permit of the printing of single photo- 85 graphs or a group or series of photographs 90 from a single film or roll of films, and of the changing of the mask or light transmitting space to suit the size and character of negative which is being printed from. It will further be evident that the invention pro- 95 vides a machine which accomplishes all of the other stated objects in a thoroughly ef- 100 ficient manner, and in addition is adapted for the printing of photographs from glass negatives without in any manner altering the construction of the machine.

I claim:

1. In a photographic printing machine, a light box having a light transmitting opening, a cylinder having masking portions and revolvably mounted on said box to bring different masking portions thereof into line with said opening, relatively adjustable shutters within the cylinder, said shutters being relatively adjustable in an arc concentric with the cylinder to vary the size of said opening, and means for relatively adjusting said shutters.

2. In a photographic printing machine, a light box having a light transmitting opening, paper feeding mechanism for feeding paper to said opening, a combined paper and negative clamping device movable toward and from the opening, and mechanism for simultaneously actuating the paper feeding mechanism and clamping device, said mechanism being operative to move the paper and clamping device in planes sub- 110 stantially at right angles to each other.

3. In a photographic printing machine, a light box having a light transmitting opening, paper feeding mechanism, a paper and negative clamping device, mechanism for simultaneously actuating the feeding mecha- 115 nism and clamping device, and means form- 120 125 130

ing part of said mechanism for varying the throw thereof.

4. In a photographic printing machine, a light box having a light transmitting opening, a cylinder having masking portions and revolvably mounted on said box to bring different masking portions thereof into line with said opening, relatively movable segmental shutters within the cylinder adjustable on arcs concentric with the cylinder with relation to said light opening, and means for simultaneously adjusting said shutters.

5. In a photographic printing machine, a light box having a light transmitting opening, a mask cylinder having masking portions revolvably mounted on said box to bring different masking portions thereof into line with said opening, and means on said box for holding a negative and sheet of paper in position for printing.

6. In a photographic printing machine, a light box having a light transmitting opening, a clamping device movable with relation to said opening, and a spring pressed yielding auxiliary clamping member on said clamping device.

7. In a photographic printing machine, a light box having a light transmitting opening, paper clamping means movable with relation to said opening, paper feeding means for feeding paper to a position between said light transmitting opening, means for conjointly operating said paper feeding and paper clamping means, and means for varying the feeding action of the paper feeding means.

8. In a photographic printing machine, a light box having a light transmitting opening, means for supporting and bringing a film into position in line with the opening, a paper feeding mechanism, a combined paper and film clamp, and means for variably adjusting said feeding mechanism and paper clamping device in unison.

9. In a photographic printing machine, a light box having a light transmitting opening, a paper feeding mechanism including a swinging arm, means for varying the throw of said arm, a paper and negative clamping device movable with relation to the light opening to clamp and release the paper and connecting means between said

device and the swinging arm for actuating said device simultaneously with the paper feeding mechanism.

10. In a photographic printing machine, a light box having a light transmitting opening, clamping means, paper feeding means, and means for operating said clamping and paper feeding means in unison.

11. In a photographic printing machine, a light box having a light transmitting opening, clamping means movable with relation to the opening, paper feeding mechanism for feeding paper between said clamping means and opening, and controlling means for varying the throw of the paper feeding mechanism.

12. In a photographic printing machine, a light box having a light transmitting opening, paper feeding mechanism including a roll, a paper and negative clamping device, mechanism for simultaneously actuating the feeding mechanism and clamping device, and means forming part of said mechanism for varying the throw of the feeding means and limiting the motion thereof.

13. In a photographic printing machine, a light box having a light transmitting opening, a pivoted clamping device movable toward and from the opening, a paper feeding mechanism including a lever, pawl and ratchet mechanism actuated by said lever, means for varying the throw of the lever, and means for operating the clamping device and paper feeding means in unison.

14. In a photographic printing machine, a light box having a light transmitting opening, a clamping device pivoted for movement toward and from the same, paper feeding mechanism, a pivoted guide for the paper, means for normally holding the guide in working position, and means for operating the clamping device, said clamping device and guide member being adjustable to an out of the way position, substantially and for the purpose described.

In testimony whereof I affix my signature in presence of two witnesses.

ALBERT SLETTEN.

Witnesses:

JOHN G. PFEFFER,

JOHN AARSTAD
